UNITED STATES PATENT OFFICE.

JOHN PLEVA, OF NEWARK, NEW JERSEY.

LIFE-BOAT.

1,096,192.

Specification of Letters Patent. Patented May 12, 1914.

Application filed January 2, 1914. Serial No. 809,924.

To all whom it may concern:

Be it known that I, JOHN PLEVA, a subject of the Emperor of Austria-Hungary, residing at Newark, in the county of Essex 5 and State of New Jersey, have invented certain new and useful Improvements in Life-Boats, of which the following is a specification.

This invention relates to certain new and 10 useful improvements in life boats.

An object of the invention is to suspend a weight or equivalent means from the bottom of a boat to render the same stabilized at all times.

15 A further object of the invention is to provide a life boat with a stabilizing plate suspended from the bottom thereof and providing the plate with a plurality of valves opening in opposite directions upon opposite sides of the center line thereof.

A still further object of the invention is to provide a life boat with adjustable bars or rods to be extended laterally thereof, constituting hand holds or grips for persons 25 entering the boat.

With the above and other objects in view which will appear as the nature of the invention is better understood, the same consists in the novel construction, combination 30 and arrangement of parts to be hereinafter more fully described and then claimed, reference being had to the accompanying drawings by like characters throughout the several views and wherein—

35 Figure 1 is a side elevational view of a life boat embodying my invention. Fig. 2 is a top plan view of the same. Fig. 3 is a cross sectional view taken on the line X—X of Fig. 1, illustrating the manner of attaching my invention to a boat. Fig. 4 is a top plan view of the stabilizing plate detached. Fig. 5 is a perspective view illustrating the modification of the stabilizing plate, and Fig. 6 is a cross sectional view of 45 the boat with a cover attached thereto.

Referring more specifically to the drawings, the reference numeral 10 indicates a life boat of usual construction provided with the bottom 11 and side seats 12. Each end of 50 the boat has mounted upon the gunwale thereof suitable standards 13 to support a sheave 14, the sheave being operated by suitable crank handles 15. Secured as at 16 to the gunwales of the boat 10 midway of 55 the same are a pair of arms 17 suitably

curved to have their meeting ends 18 lie directly beneath the central line of the boat 10. The upper ends of the arms 17 are provided with angular bends as at 19, said bends contacting the gunwales of the boat 60 to prevent all undue movement thereof. Suspension legs 20 terminate at their upper ends as at 21 in an eye, which eye is adapted to be received between the meeting ends 18 of the arms 17 and be held in such position by the pin 22. The legs 20 are spread apart at the lower ends and are suitably connected to the plate 23. This plate is preferably hinged at its center line as at 24. Each side of the plate is provided with a 65 plurality of openings adapted to be closed by valves 25, preferably as shown of the flap valve type. It is to be noted that the flap valves 25 on one side of the central line 24 open in the opposite direction to the 70 valves on the other side of said plate. Suspended beneath the plate 23 by a link or other suitable fastening means as at 26 is a weight 27, which weight tends to keep the plate 23 in a line directly beneath the pivot 75 18. The legs 20 are provided intermediate their ends with suitable eyes 20' and connected to said eyes 20' carried by said legs are the chains 41 which extend upwardly 80 and pass over and are secured to the sheaves 85 14. Mounted upon the gunwales intermediate the arms 17 and both ends of the boat are the clamps 28 and to be received within said clamps 28 are the adjustable bars 29, which bars are further held in adjusted position by the clamps 30 carried thereby. 90

A modified form of the plate and its suspension means is shown in Fig. 5 and comprises the flat plate 31 weighted as at 32 and provided with a plurality of flap valves 33 95 opening in opposite directions as described in connection with the form shown in Fig. 4. In lieu of the supporting legs 20 above described the plate 31 in this instance is supported at each corner by the chains 34, 100 which chains are brought together at a point directly above the center of the plate 31 and connected to a single chain 35 which constitutes the suspension device carried by the boat. 105

My invention is particularly adaptable to small boats such as life boats which many times encounter high and rough seas and with this object in view my invention aims to render the boat substantially stable at all 110

times. It will be noted that the legs 20 shown in Figs. 1 and 3 permit a slight swinging movement both forwardly and rearwardly but no lateral movement is permitted owing to the eye connection 21 with the lower ends 18 of the arms 17. Should the boat 10 have any tendency at all to rock or roll, the same will be retarded by the plate 23. When one end of the plate 23 is 5 elevated or swings on its pivot 22, the end of the plate descending will have a practically free movement by the valves on said side opening, while the valves upon the other side of said plate will remain closed and 10 retard the upward movement thereof. Should either of the chains 41 become slack, the weight 21 will tend to centralize or dispose the plate 23 directly beneath the pivot 22. Should it be desired to extend the arms 15 29, the clamps 28 and 30 are loosened to permit the said arms to move laterally of the boat and in this position the arms may constitute either hand holds or a means to prevent the boat 10 from colliding with another 20 vessel.

The boat 10 shown in Fig. 6 has the hand holds 45 projecting laterally therefrom, at a point below the gunwales and carried by said boat is a collapsible cover 46 suitably supported at the longitudinal pivot point 47.

The cover 46 may be utilized in inclememt or stormy weather.

While I have shown the preferred embodiment of my invention, I do not wish to confine myself thereto, as various forms, 35 modifications and arrangements of the parts as shown may be had without departing from the spirit and scope of the invention as claimed.

I claim:—

1. In a life boat, suspension means carried thereby, a plate connected to the lower end of said suspension means, said plate provided with openings upon each side of the center line thereof, flap valves for closing 45 said openings, the valves upon one side of the center line opening in opposition to the valves upon the other side and a weight suspended from said plate.

2. The combination with a life boat provided with lateral adjustable arms, of a suspension device carried by said boat and a weighted and valved stabilizing plate connected to the suspension device.

In testimony whereof I affix my signature 55 in presence of two witnesses.

JOHN PLEVA.
